Patented Aug. 12, 1913.

UNITED STATES PATENT OFFICE.

GUSTAVE ADOLF MAYER, OF NEW DORP, NEW YORK.

HUMIDIFIER.

1,070,275.

Specification of Letters Patent. Patented Aug. 12, 1913.

Application filed February 11, 1913. Serial No. 747,640.

To all whom it may concern:

Be it known that I, GUSTAVE ADOLF MAYER, a citizen of the United States, and residing at New Dorp, borough of Richmond, in the county of Richmond and State of New York, have invented a new and Improved Humidifier, of which the following is a full, clear, and exact description.

My invention relates to a means for increasing the humidity of the atmosphere in rooms heated by radiators, and more particularly to a device embodying a water receptacle and attachable directly to a radiator, to be sustained directly adjacent thereto, with a view to the efficient and rapid evaporation of the water, to thus bring the air in the room to a proper condition for breathing.

It is a design of my invention to provide a device of the indicated character which will present a minimum degree of projection beyond the radiator, and yet be located in the open, to permit of the rapid evaporation.

It is also a design of my invention to give the body or water container of the humidifier a form that will be ornamental, and at the same time present members to be received partly between the radiator sections.

It is a further design of my invention to provide a suspending and retaining means which will be readily attachable to and detachable from the radiator, and adapted to engage standard elements in the radiator so as to make the device applicable to radiators in general use.

The invention also has for its design the provision of suspending and retaining means so formed and so connected with the body or water container, as to firmly engage and steady the said container when the device is in use, but which may be folded to a position close against the body or container so that the complete device may be folded into small compass when not in use, or when being shipped.

The invention will be particularly explained in the specific description herein-after to be given.

Reference is to be had to the accompanying drawings forming a part of this specification, in which similar characters of reference indicate corresponding parts in all the views.

Figure 1 is a front elevation of a humidifier embodying my invention, showing the

same attached to a radiator; Fig. 2 is a transverse vertical section; and Fig. 3 is a horizontal section.

In forming the device in accordance with my invention, the body or container 10 is made tubular and closed at the bottom 11 to be water-tight, the top being open for receiving a supply of water and for the free evaporation of the water. The cross-sectional dimensions of the container are such that the same will be accommodated between two sections 12 of the radiator, to extend partly within the plane of the front of the radiator. Preferably, the container is formed with vertical corrugations 10^a, for the purpose of snugly positioning it against the radiator sections as well as for affording strength, and to give the body an ornamental character.

A suspending and retaining means is provided in the form of a lateral arm at the rear of the body, to enter between adjacent pairs of radiator sections 12. Preferably, said arms consist of resilient rods or wires 14 twisted together as at 13. The free rear ends of the arms 14 diverge as shown clearly in Fig. 3, preferably on curved lines and terminate in heads 15 of essentially hooked form, which are produced by returning the ends of the arms, said terminal ends thus formed serving to engage the rear radiator sections 12 and lie against the outer surface of the latter. Since ordinarily the radiator sections will have vertical ribs 12^a at their outermost surfaces, these ribs will be engaged by the hook-like terminal ends 15. In practice, the retaining and suspending device consisting of the arms 14 or their equivalent, is passed through the radiator from front to rear, above the horizontal bolt 16 or rod 16 of the radiator, so that the arms will have effective engagement with the radiator by resting upon the bolt 16; and secondly, by the engagement of the hook-like ends 15 with the ribs 12^a or equivalent members of the radiator sections.

The arms 14 extend freely through separate holes 17 formed in the container 10 at the rear, near the upper end of the said container, and within the container the arms are secured to or formed integral with a head 18, which may be produced by forming the wires into a loop, as indicated in Fig. 1, the said head being at approximately right angles to the arms 14, so that when the lat-

ter are in the raised position, to engage the radiator, the head 18 will bring up against the inner surface of the container 10, as clearly shown in Figs. 2 and 3. Thus the 5 head 18 limits the upward movement of the arms 14, and will sustain the container 10 in a substantially vertical position on the face of the radiator. The arms 14 are adapted to rock vertically in the holes 17, 10 that they may fold to the lowered position indicated in dotted lines in Fig. 2, whereby the device will be compact for storing or for shipping.

In applying the device to the radiator the 15 suspending and retaining device is raised from the dotted position until the head 18 contacts with the inner surface of the container, and the complete device may then be turned to bring the diverging free ends of the 20 arms 14 into approximately vertical alignment, or said arms may be brought into vertical alignment by twisting the same; the arms are then entered between the radiator sections, above the usual bolt 16, and the arms 25 are then brought to the horizontal position shown in Figs. 2 and 3 and permitted to rest on the bolt 16 while the hook-like ends 15 are caused to engage the rear radiator sections at the back thereof. The container 30 will thus be held suspended snugly between two adjacent sections and will project but little beyond the latter. The open top of the container affords ready access to the latter for refilling.

35 The described construction affords a practical means for carrying my invention into effect in a simple form, and I would state in conclusion that I do not limit myself strictly to the minor details herein illustrated, since 40 manifestly the same can be considerably

varied without departing from the spirit of the invention.

Having thus described my invention, I claim as new, and desire to secure by Letters Patent:

1. A humidifier for radiators, comprising a tubular container adapted to fit between adjacent sections of the radiator and provided with an arm adapted to pass between adjacent pairs of radiator sections and having a bifurcated end, the members of which diverge and terminate in heads for engaging the two radiator sections in rear of those engaged by the container. 45

2. A humidifier for radiators comprising a container, and an arm projecting loosely through the container and provided within the container with a right angular member adapted to engage the inner surface of the container when the arm is swung into horizontal position, said arm terminating in diverging members with heads at their ends. 50

3. A humidifier for radiators, comprising a container provided with two holes adjacent its upper end, and a securing arm formed of a piece of wire bent upon itself at about its 55 center of length and formed with a right angular loop, the members of the wire being passed through the holes of the container with the loop inside of the same and then twisted together outside of the container, the free ends of the wire diverging and formed with heads. 60

In testimony whereof I have signed my name to this specification in the presence of 70 two subscribing witnesses.

GUSTAVE ADOLF MAYER.
